UNITED STATES PATENT OFFICE

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

COVER FOR LOOSE-LEAF BOOKS AND METHOD OF MAKING SAME

Application filed July 2, 1926. Serial No. 120,053.

This invention relates to loose-leaf books such as temporary binders, loose-leaf ledgers, etc., which have a back, usually rounded, and sides hinged to the back. It is desirable in 5 such books to make the cover of leather or leather substitute so as to conceal the metal as far as possible, and to that end to embed the metal within the cover material.

While the present invention is especially 10 designed for covers having metal hinges, it is to some extent applicable to those having flexible hinges.

Prior inventions relating to such metal 15 hinged book covers are set forth in my pending applications Nos. 430,581, filed December 13, 1920, and 10,586, filed February 20, 1925.

The nature of the invention will be made apparent as the description proceeds.

The accompanying drawings illustrate the 20 preferred embodiment of the invention.

Figure 1 is a transverse section of the back portion of a loose-leaf ring book and cover, showing the rings closed and the book cover partly open.

Fig. 2 is a plan, partly broken away in section, of the book back, viewed from the inside, and the engaging portion of one of the sides of the book, these members being separated at their hinges for greater clearness.

Fig. 3 is an edge view of the back, looking from the line 3-3 in Fig. 2, and

Fig. 4 is an edge view of the side of the cover looking from the line 4-4 in Fig. 2.

Fig. 5 is a perspective view of the back, 35 the leather being partly removed to show the metal back plate.

Figs. 6, 7 and 8 are transverse sections of the back showing different stages in the manufacture thereof.

Referring to the drawings, the loose-leaf 40 binder consists of a cover A of leather or other suitable material, and loose-leaf binding rings, prongs or the like illustrated conventionally at B, as being of a well-known construction, the divided rings being engaged by a spring plate C to press them together when closed and hold them open when opened. The back plate D is also shown fastened against the inner face of the cover back.

The cover A is composed of a back a and

sides b, b hinged together at c, c by metal hinges, including hinge pintles, in a usual way. The book back a is commonly and preferably made with an externally convex curve as shown.

Within the back a is embedded a metal stiffening plate d which may also serve as a hinge plate, and within the sides are embedded metal plates e, e. These several plates d, e, e are shown as formed with hinge ears 60 c', c'' respectively, which, when the ears are brought into alignment, may be united by the usual hinge pin or pintle.

It has been customary heretofore to apply hinge plates such as d, e, e against the inner side or face of the back and sides respectively; or to construct hinge plates in U-form embracing the edge portions of the respective back and sides. According to the present invention, the plates are embedded within the 70 thickness of the leather or other cover material.

Assuming that the cover, back, and sides are made of suitably thick leather, the method of manufacture follows somewhat closely 75 that set forth in my pending application No. 100,566, filed April 8, 1926, which, however, applies solely to the means of inserting a back plate or stiffening plate within the back portion of an integral cover. According to 80 the present invention when leather is the cover material, the back a of the cover is first treated by cutting a groove f along its inner side at preferably the middle, and extending approximately half way through its thickness; then a suitable cutting tool is inserted 85 in this groove and carried through toward the edges of the back a on each side of the groove, whereby to separate its inner portion from its outer portion and form be-

tween them a pocket. This severing portion may be carried entirely through the ends of the back, but it is preferable to stop short of the ends, as shown at g, so as to form a closed pocket. The pocket also stops short of the edge at which the hinge connection is to be made, as shown at h. At the places corresponding to the hinge eyes c', the edges of the cover material are cut entirely through. The cutting operation thus described may be 100

performed by a slitting knife inserted at the groove *f* on the one side, and later on the other side; or it may be performed by bending the cover material backwardly over a plate and then cutting the pockets with rotary saws or disk cutters, as fully described in my said application Serial No. 100,566. After the two pockets are cut in the manner just described, the back plate *d* is inserted 10 into these pockets and its hinge eyes *c'* pushed through the openings thereof so as to protrude therefrom as shown in Fig. 2. For this purpose either one of the pockets on its inner side may be cut open along lines *m m* in 15 Figs. 2 and 5 to form a flap to facilitate the insertion of the inner plate, this flap being afterward cemented down; or both sides may be thus cut to form flaps if desired.

The cover sides *b*, *b* are treated in similar 20 manner, in this case the groove here lettered *f'* being cut at any convenient distance back from the edge, and the pocket extending thence to the edge being formed in the same manner as for the back, except that the edge 25 portion is cut through in different positions corresponding to the positions of the hinge eyes *c''* in Fig. 2. According to the width desired for the plate *e*, the pocket may be extended in the opposite direction by a similar cutting operation, as shown by the line *i* 30 in Fig. 2, in which case the flap overlying the plate may be cut free along lines *m' m'* in Fig. 2. The plate *e* may then be inserted 35 in the pocket formed in the side in the same manner already described for the plate *d*.

After the insertion of the plates *d*, *e*, the leather may be cemented down by any suitable cementing material.

It is preferable to form the back *a* either 40 flat, as shown in Fig. 6, or outwardly concave, as shown in Fig. 7, the latter form having some advantages with respect to the insertion of the plate *d*. When formed in either way, it should be convexed to approximately the shape shown in Fig. 8 by pressing or striking between suitable dies. This operation will bring the edges of the inner flaps 45 on opposite sides of the groove *f* together, as shown in Figs. 5 and 8, if the groove *f* has been cut of suitable width. The grooves *f'* 50 for the sides cannot be thus brought together and may desirably be filled by cementing in a strip of leather, as shown at *j*. If the groove *f* in the back is not fully closed by the bending operation, it may also be filled in similar 55 manner if desired; but ordinarily this will not be necessary for appearance sake because usually an inner plate *D* is employed which will wholly conceal this groove if left open.

It is usual in such books to provide a back plate with some means for attaching to it the plate *D*, and this is commonly accomplished by forming it with ears or tongues *k*, *k* struck 65 up at right angles and entering through slots

in the inner part of the leather and passing through holes in the plate *D* and being then bent down to clinch this plate to the book back.

The present invention makes a very strong, 70 serviceable cover for loose-leaf binders which is well suited for large books and those having heavy service, such as ledgers. It has the advantage of concealing the metal plates as nearly as it is possible to conceal them, only 75 the hinge ears being visible on the exterior. It has also the advantage that the leather, being exterior to the metal, takes all the wear, and the metal parts do not come in contact with desks or other furniture which might be 80 scratched.

It will be understood that the showing in the drawings is somewhat ideal, the leather in actual practice being made larger or given a looser fit with the metal plates than would 85 appear from the figures. Thus, in Figs. 6 or 7 the leather must have sufficient fullness on the lower or outer side so that when brought to the shape shown in Fig. 8, the leather on the exterior (being commonly the grain side 90 of the skin) will not be unduly stretched. Also, by giving the leather sufficient fullness, the insertion of the metal plates is facilitated. It is not necessary that the metal plates fill 95 the ends of the pockets, that is, come directly to the end walls *g* of the pockets, as appears in Fig. 2. Nor is it essential that the hinge eyes *c' c''* project outside the cover material.

If the book is not of the metal hinge type, it is only necessary to omit the hinge eyes *c'* 100 from the metal back plate or stiffening plate *d*, in which case of course the cover material will only have the pockets for receiving the plate *d*, the side plates *e* being omitted and there being no pockets to receive 105 them.

The invention may be otherwise applied within the skill of those familiar with this art, and without departing from its essential features which are expressed in the following 110 claims.

I claim as my invention:

1. A book cover having a back and sides hinged together, the back being formed with a pocket within the material, and the hinge means including a metal hinge plate introduced into said pocket and having hinge eyes adjacent the edges of the material. 115

2. A book cover having a back and sides hinged together, the sides being of integral material split to form pockets within the thickness of the material, such pockets being closed at the edge of the side next the back and open remote therefrom, and metal hinge plates introduced into said pockets from the openings thereof and having hinge eyes adjacent the closed side of the pockets, said eyes exposed for engagement with reciprocal hinge eyes on the book back. 120

3. A book cover having a back and sides 130

hinged together by interengaging metal hinge plates, the back and sides being of integral material split to form pockets within the thickness of the material, said pockets closed along the hinged edges except for openings admitting the hinge eyes on said plates, and said pockets open back of said edges to permit the insertion of such plates, and metal hinge plates introduced into said pockets and having reciprocal hinge eyes entering said recesses in the pockets, and adapted upon the aligning of the hinge eyes to receive a hinge pin.

4. The method of making book covers comprising a back and sides hinged together, consisting in cutting pockets within the thickness of the back and sides, with openings through said pockets at the hinge edges, inserting metal plates into said pockets having hinge eyes which coincide with said openings, and uniting the respective hinge eyes to form hinges.

5. The method of making book covers comprising a back and sides hinged together, consisting in cutting a pocket within the thickness of the back, with openings through said pocket at the hinge edges, and inserting a metal plate into said pocket having hinge eyes which enter said openings.

6. The method of making a book cover having a back and sides hinged together, consisting in cutting pockets within the thickness of the sides with openings at the hinge edges and inserting hinge plates in said pockets with their hinge eyes entering said openings.

7. The method of making a book cover having a back and sides hinged together, the back being convex, consisting in cutting the material of the back between its inner and outer faces to form a pocket for receiving a hinge plate, inserting a hinge plate in said pocket with its hinge eyes projecting beyond the edges of the back, and bending the back to externally convex form.

8. The method of making a book cover consisting of a back and sides hinged together, consisting in cutting on the inner face of the cover material a longitudinal groove, then cutting from said groove between the outer and inner faces of the material to form a pocket for the reception of a metal hinge plate, and inserting such plate in said pocket.

9. The method according to claim 8, with the added step of filling the groove upon the inner side of the cover to conceal the plate.

10. The method of making a book cover consisting in cutting the material of the back on one side to form a longitudinal groove, splitting the material from this groove outwardly in both directions to form pockets, the open sides of which face each other along the middle, and cutting from the middle in one direction near each end to form a free flap which can be turned back, inserting a

metal back plate into the other pocket, and turning down the said free flap upon the plate.

11. The method of making a book cover consisting in forming a longitudinal groove in the inner face of the book back, splitting the material from said groove outwardly in both directions to form pockets, inserting a back plate of otherwise than the ultimate concave form in such pockets, and afterward bending the back with such enclosed plate to concave form.

In witness whereof, I have hereunto signed my name.
